CLAIM

The ornamental design for a food holding cabinet as shown and described.

DESCRIPTION

FIG. 1 is a right perspective of a food holding cabinet of the present disclosure;

FIG. 2 is a front view of the food holding cabinet;

FIG. 3 is a right side view of the food holding cabinet;

FIG. 4 is a top view of the food holding cabinet;

FIG. 5 is a rear view of the food holding cabinet; and,

FIG. 6 is a left side view of the food holding cabinet.

The dash-dash-dash broken lines depict portions of the food holding cabinet that form no part of the claimed design. The dash-dot-dash broken lines depict boundaries of the claimed design and form no part thereof.

In other embodiments, other portions or other combinations of portions of the food holding cabinet are shown in solid lines with the remainder of the food holding cabinet being shown in broken lines.
